LOCK

Manuel Ramos, Forest City, Pa., assignor of one-third to George Ganfororo, Archbald, Pa., and one-third to Manuel G. Gaselas, Forest City, Pa.

Application June 16, 1933, Serial No. 676,184

1 Claim. (Cl. 70—74)

This invention relates to a lock, the general object of the invention being to provide a lock with a pair of bolts and a key for operating the bolts, with means whereby the key must be placed in different positions to operate the bolts so it will be difficult for one not familiar with the lock to open it, even though he has the right key.

This invention also consists in certain other features of construction and in the combination and arrangement of the several parts, to be hereinafter fully described, illustrated in the accompanying drawings and specifically pointed out in the appended claim.

In describing the invention in detail, reference will be had to the accompanying drawings wherein like characters denote like or corresponding parts throughout the several views and in which:

20 Figure 1 is a top plan view of the lock.

Figure 2 is a section on line 2—2 of Figure 1.

Figure 3 is a plan view with the cover removed.

Figure 4 is a fragmentary sectional view showing the key in place.

25 Figure 5 is a fragmentary plan view, with the small casing removed.

In these drawings, the casing is shown at 1 and the cover plate at 2. The base of the casing is formed with a rear extension 1' and the front wall is formed with two openings 3 and the rear wall with two openings 4. A pair of bolts 5 and 6 is located in the casing and have their ends passing through the openings 3 and 4, these ends being reduced, as shown. Each bolt is formed with a projection 7 on its outer edge to provide a shoulder and with a projection 8 on its inner edge which forms a shoulder for engaging the inner wall of the front of the casing, when the bolt is projected, to limit projecting movement of the bolt. The inner edge of each bolt is also formed with an inwardly bowed part 9 which extends from the projection 8 to a notch 10 also formed in the inner edge of the bolt and a bar 11 passes across the mouth of the notch.

A pawl 12 is pivoted in the casing adjacent the outer edge of each bolt and is adapted to engage the shoulder formed by the projection 7 to hold the bolt in projected position. The pawl is moved into engagement with the shoulder by the spring 13. Each pawl carries a laterally extending wing 14 which extends over the bolt and over the recess formed by the inwardly bowed part 9. The spring pressing the pawl 12 against the rounded part of the projection 7,

acts to hold each bolt in projected position, as shown in Figure 3.

A tubular member 15 passes through the casing and the cover plate and through a small casing 16 formed on the cover plate and has a reduced end passing through the base of the casing and held in place by the nut 17. This member is formed with a slot 18 to enable the ward 19 of the key 20 to be inserted into the tubular member. This ward is notched as shown, and this notch will receive the bridge piece 11 of the bolt.

The top 2 of the casing 1 is formed with a pair of oppositely arranged slots 21 and the cover of the small casing is formed with a single slot 22 which is arranged at right angles to the slots 21.

Thus it is necessary to place the key in the tubular member 15 and to turn the parts to a position where the ward 19 will enter the slot 22 in the top of the small casing. The space formed by the small casing is of sufficient size to receive the ward and to permit turning movement thereof. After the ward has passed into the small casing, the parts are again turned so that the ward can be passed through one of the slots 21 to place the ward in engagement with one of the notches 10. Then a further turning movement of the key will cause the ward to project one of the bolts, and when the bolt is so projected, its pawl will engage the projection 7 and the bolt will be held in this position. As will be seen, the key is first inserted into the tubular member and the tubular member turned to a position where the ward of the key can enter the notch 22 and then the key is given a quarter turn rearwardly so that the ward can pass through the rearmost slot or notch 21. The key is then turned counter-clockwise to project the bolt 5. The key is turned a half revolution to project the bolt, which brings the ward under the front slot 21. The key is then partly pulled from the tubular member 15 into the casing 16 and then the key is given another half revolution so as to bring the ward over the rear slot 21. The key is then pressed inwardly so that the ward will pass through the rear slot 21 and then the key is given a half revolution clockwise so as to project the bolt 6. Then the key is pulled outwardly to cause the ward to pass through the front slot 21, after which the key is given a quarter turn to permit the ward to be pulled through the slot or notch 22.

When the lock is to be unlocked, the key is inserted and as before described, it must be

turned to a position where it will engage the inner end of a wing 14 so that it will exert pressure upon the wing to move the pawl to inoperative position so that the pawl will be freed from the projection 7 and then further turning movement will retract the bolt. The key is then manipulated as before described to retract the second bolt.

By slightly changing the shape of the inner edges of the bolts, the lock can be constructed for use with different keys and by constructing the bolts with steel bars loosely inserted therein, the bolts could not be sawed in an attempt to open the closure provided with the lock.

It is thought from the foregoing description that the advantages and novel features of the invention will be readily apparent.

It is to be understood that changes may be made in the construction and in the combination and arrangement of the several parts, provided that such changes fall within the scope of the appended claim.

What I claim is:—

A lock of the class described comprising a casing having upper and lower openings in its front and rear walls, a pair of bolts slidably arranged in the casing and having blunt front ends passing through the front openings and reduced rear ends passing through the rear open-

ings, a shoulder forming projection on the inner edge of each bolt for engaging the front wall for limiting outward movement of the bolt and said inner edge of each bolt having a notch therein for receiving a ward of a key, said notch being spaced rearwardly from the projection and said inner edge having a concave recess therein located between the notch and the projection, a bridge piece spanning the notch, a projection on the outer edge of each bolt located opposite the recess and having a straight rear wall forming a shoulder and a rounded front wall, upper and lower pawls pivoted in the casing between the bolts and the upper and lower side walls of the casing, a spring attached to each pawl and engaging a side wall of the casing and pressing the pawl against the rounded front wall of the projection when the bolt is retracted and causing the front end of the pawl to engage the straight rear wall of the projection when the bolt is projected, said casing having a keyhole therein located between the bolts and a wing of rigid construction connected with each pawl and extending across a bolt and having a rounded free end extending across a recess of a bolt for engagement by the ward for moving the pawl to releasing position.

MANUEL RAMOS.
